(57) **CLAIM**

The ornamental design for a football helmet vehicle ornament, as shown and described.

DESCRIPTION

FIG. 1 is a perspective view of the football helmet vehicle ornament of my new design;

FIG. 2 is a left side elevation view thereof;

FIG. 3 is a right side elevation view thereof;

FIG. 4 is a right side elevation view thereof with surface ornamentation depicted in broken lines that is no part of the claimed design;

FIG. 5 is a front elevation view thereof;

FIG. 6 is a rear elevation view thereof;

FIG. 7 is a top plan view thereof; and,

FIG. 8 is a bottom plan view thereof.

In the drawings, the broken lines in FIG. 4 depict surface

ornamentations that form no part of the claimed design.

In the drawings, the broken lines in FIG. 8 depict portions

of the article that form no part of the claimed design.

1 Claim, 6 Drawing Sheets
